UNITED STATES PATENT OFFICE.

WILLIAM I. FERRIS, OF WESTFIELD, NEW JERSEY.

DESIGN FOR A POUR-OUT BOTTLE-STOPPER.

47,716.

Specification for Design.

Patented Aug. 17, 1915.

Application filed October 29, 1914. Serial No. 869,322. Term of patent 14 years.

To all whom it may concern:

Be it known that I, WILLIAM I. FERRIS, a citizen of the United States, and a resident of Westfield, in the county of Union and State of New Jersey, have invented a new, original, and ornamental Design for a Pour-Out Bottle-Stopper, of which the following is a specification, reference being had to the accompanying drawing, forming part thereof, in which—

Figure 1 is a perspective view of the pour

out stopper illustrating my new design; and Figs. 2 and 3 are side and rear elevations thereof.

I claim:

The ornamental design for a pour out bottle stopper, substantially as shown.

WILLIAM I. FERRIS.
